[57] CLAIM

The ornamental design of the combined bolt and plastic cap, as shown and described.

DESCRIPTION

FIG. 1 is a perspective view of a combined bolt and plastic cap showing our new design;

FIG. 2 is a top plan view thereof, the bottom plan view being a mirror image thereof;

FIG. 3 is a side elevational view thereof; the opposite side being a mirror image thereof;

FIG. 4 is an end elevation view of the left end thereof;

FIG. 5 is an end elevational view of the right end thereof;

FIG. 6 is a perspective view of a modification of the combined bolt and plastic cap of FIG. 1;

FIG. 7 is a top plan view of FIG. 6, the bottom plan view being a mirror image thereof;

FIG. 8 is a side elevational view of FIG. 6, the opposite side being a mirror image thereof;

FIG. 9 is an end elevational view of the left end of FIG. 6; and,

FIG. 10 is an end elevational view of the right end of FIG. 6.
